HENRY FELTHOFF AND LUCAS D. TINGLEY, OF PRINCE WILLIAM,
INDIANA.

Letters Patent No. 90,517, dated May 25, 1869.

IMPROVED DITCHING-MACHINE.

The Schedule referred to in these Letters Patent and making part of the same.

To all whom it may concern:

Be it known that we, HENRY FELTHOFF and LUCAS D. TINGLEY, of Prince William, in the county of Carroll, and State of Indiana, have invented certain new and useful Improvements in Ditching-Machines; and do hereby declare the following to be a clear and exact description thereof, reference being had to the accompanying drawings, in which—

Figure 1 is a plan view of our ditching-machine, complete in all of its parts;

Figure 2 is an end elevation of the same; and

Figure 3, a side elevation.

In each of the several figures, similar letters of reference denote like parts.

Our invention relates to that class of machines employed for ditching or excavating the earth, the spades of the same being adjustable.

It consists of a strong frame, supported by two tread-wheels at or near the centre of each side thereof, upon which frame are secured standards for supporting the slides, serving as bearings for the axis of the spade-wheel, the spades of which, when in contact with the earth, are, together with the wheel, rotated by the forward movement of the machine;

Also, in the devices employed for the vertical adjustment of the spade-wheel, and thereby regulating the depth of the cut of the spades; and

Also in the construction and arrangement of an automatic scraper for cleaning the spades, and preventing their clogging.

A is the frame, or bed of the machine, composed of stout timbers mortised together, and supported by two small wheels x, centrally located on either side of the machine.

Immediately in the rear of the front piece of the machine-frame, is a piece extending longitudinally across it, marked B, to which, and to the outer, or rear cross-bar A' of the frame, are secured the upright standards C, each provided with a slit, or groove, s, extending nearly their entire length, to receive the vertical slides F, in which the axis of the spade-wheel H has its bearings.

Suitable apertures are provided in either side of each of the standards C, corresponding with similar apertures formed in the slides F, to receive pins t, for adjusting said slides, and thereby regulating the adjustment of the spade-wheel H, which has the bearings of its axle in suitable boxings on the lower end of the vertical slides F.

The upper ends of the slides F are provided with an adjustable bolt, z, having a thread cut on one end to receive the nuts c, which retain them in place, and a flat circular head, in which is cut a female screw, through which works a vertical screw-rod a'. These latter, impinging upon the tops of the standards, in which work the vertical slides, in connection with the pins t, constitute the device for adjusting vertically the axle of the spade-wheel.

The spade-wheel H has its bearings in the lower ends of the slides F and L, and may be entirely of

metal, or its body of wood, having annular rims h h and suitable spades, or scoops i, of metal.

The rims h serve to cut into the earth the required width of the ditch, and in conjunction with the spades, furnish a suitable scoop for the retention of the earth while being elevated.

The spades i are formed of metallic pieces, the sides of which are slightly curved inwardly, and are secured at an angle of about forty-five degrees to the periphery of the wheel H.

I represents a curved metallic trough, located immediately in the rear of the wheel H, which serves as an adjunct for lifting the earth by assisting to conduct and retain it in the spades.

The cog-wheel K, secured to the axle of the spade-wheel, is adjusted vertically, by means of the slide L, in the standard M, in the same manner and by the same devices as described for adjusting the slides F.

N is a combined pinion and axle, having its bearings in one of the uprights C and standards O, in such a manner as that the pinion shall be in gear with the cog-wheel K by which it is operated.

The crank-wheel P, secured to one end of the shaft of pinion N, connects with an elbow-lever, Q, having its fulcrum, which is adjustable, at W.

One end of the elbow-lever Q plays within a suitable slot, or groove in the standard T, which is secured to the frame A, as shown in the drawings.

The hook-shaped rake or scraper u is attached to the upper end of lever Q, and plays within the ways in the upper part of upright standard O, and which, by the motion of the spade-wheel, acts as a scraper for the spades i, removing therefrom such earth as may cling thereto and tend to impair the utility of the machine.

Secured to the angular pieces V is a metal platform, w, for receiving and conveying to one side of the ditch the earth as it is pushed off from the spades by the scraper u.

The operation of our machine is as follows, viz:

The vertical adjustment of the spade-wheel H, being such as to permit its spades to penetrate the soil to a proper depth for excavating, the weight of the machine, when moved forward, causes the annular rims h to penetrate and cut the earth, and the spade-wheel H to lift the same from the ditch, and bring the spades within the action of the rake, or scraper u, by which the earth is pushed or raked on to the angular platform W, and passes to one side of the machine.

The cog-wheel K, being secured to the main shaft of the spade-wheel H, rotates therewith, and gearing into the pinion N, operates the crank-wheel P, and thereby imparts, through the lever Q, a reciprocal motion to the rake u, which brings it alternately in line with each spade, or spade-space, as it comes up filled with earth. And in the further revolution of the wheel H, the rake is thrust sufficiently far in the required direction to push the earth on to the platform W, and, in its backward move, thoroughly cleanse or scrape the spades, as each comes in line.

A suitable trap-door, or slide on the face of the angular platform, may be so arranged as to admit light to the ditch at such point as the spades are entering the earth, for inspecting the operation of the spade-wheel, or the nature of the soil to be excavated.

Having thus fully described our invention,

What we claim as new, and desire to secure by Letters Patent, is—

1. The spade-wheel H, in combination with standards C and M, slides F and L, and adjusting-bolts and tops a', z, and e, and pins t, all substantially as herein set forth.

2. The crank P and lever Q, in combination with the scraper u, substantially in the manner and for the purpose herein set forth.

As evidence that we claim the foregoing, we have hereunto set our hands, in the presence of three witnesses.

HENRY FELTHOFF.
LUCAS D. TINGLEY.
